UNITED STATES PATENT OFFICE.

FREDERICK J. GREENE, OF RACINE, WISCONSIN.

AUTOMATIC RIVETING-MACHINE.

1,392,494.

Specification of Letters Patent.

Patented Oct. 4, 1921.

Application filed June 30, 1919. Serial No. 307,575.

To all whom it may concern:

Be it known that I, FREDERICK J. GREENE, a citizen of the United States, and resident of Racine, in the county of Racine and State 5 of Wisconsin, have invented new and useful Improvements in Automatic Riveting-Machines, of which the following is a description, reference being had to the accompanying drawings, which are a part of this 10 specification.

This invention relates to improvements in automatic riveting machines more particularly adapted for riveting edge strips of angular form in cross section to panels or 15 side members in forming trunks and similar boxlike receptacles.

In the present manufacture of trunks the side or panel portions are nailed together along their adjacent edges or to an edge 20 member by hand. This construction requires considerable time and is not as accurate nor as strong as machine work in which the parts are riveted together.

It is one of the objects of the present invention to overcome the before mentioned 25 objectionable features and to provide an automatic riveting machine with means for holding a panel while angular edge strips are riveted thereto, and also for holding the 30 panels while other panels are being riveted to the edge strips.

A further object of the invention is to provide an automatic riveting machine in which means are provided for automatically 35 and intermittently moving the panel or partly assembled trunk or the like certain predetermined distances with relation to the riveting portion of the machine to receive rivets in lines and spaced distances apart.

40 A further object of the invention is to provide an automatic riveting machine in which the panel or trunk part may be intermittently moved in lines backwardly or forwardly or at right angles thereto to permit the riveting of all edge portions of the trunk.

45 A further object of the invention is to provide an automatic riveting machine which is of simple construction, is strong and durable and is well adapted for the purpose described.

With the above and other objects in view the invention consists of the improved automatic riveting machine and its parts and combinations as set forth in the claims and 50 all equivalents thereof.

In the accompanying drawings in which

the same reference characters indicate the same parts in all of the views:

Figure 1 is a perspective view of a riveting machine embodying the improvements;

Fig. 2 is a front detail view on a larger scale of the mechanism for feeding the trunk parts laterally across the front portion of the machine;

Fig. 3 is an end view of the parts shown in Fig. 2 and also showing more fully the mechanism for feeding the trunk parts toward and away from the front portion of the machine, parts broken away;

Fig. 4 is a detail view of the means for transmitting motion from the driving shaft to the feeding mechanism;

Fig. 5 is a vertical sectional view thereof;

Fig. 6 is a perspective view of the brackets and the slideable member for holding the trunk panels while riveting the angular edge strip thereto; and

Fig. 7 is a sectional detail view of an edge portion of a trunk.

Referring to the drawings the numeral 8 80 indicates a riveting machine which comprises a base portion 9, an upstanding column 10, an outwardly and upwardly extending arm 11, an outwardly and downwardly extending coacting hammer arm 12, 85 a riveting hammer 13 and a rivet supply mechanism 14. The movable parts are actuated by the driving mechanism 15 mounted on and extending transversely of the upper portion of the machine. The portion of the machine thus far described is of ordinary 90 construction and it is not necessary to show nor describe in detail.

A transversely extending guide member 16 rigidly mounted on the upstanding column 10 beneath the anvil arm 11 carries a slideable bar 17 which is provided with an outwardly projecting guide arm 18. The slideable arm is formed with a horizontally extending T-shaped groove in cross section 100 19 for adjustably receiving the heads of adjusting bolts 20 of the guide arm 18 to permit adjustment of said guide arm on the bar. Mounted on the lower side portions of the guide arm is a transversely extending 105 slideable member 21 carrying a longitudinally extending rod 22 and forwardly from this rod project supporting arms 23. The supporting arms are of angular form in cross section and are adapted to support the 110 lower edge portions of the trunk, being riveted together.

A clutch wheel 24 connected to the driving mechanism 15 carries a loosely mounted disk 25 provided with an outwardly projecting tubular wrist pin 26. The wrist pin 5 is provided with a spring pressed bolt 27 which is adapted to enter one or the other of the two bolt openings 28 formed diametrically opposite each other in the clutch wheel 24 to permit the changing of the time of 10 movement of the rivet hammer with relation to the direction of travel of the supports 23 as it is obvious that when the bolt is positioned in the lower opening 28 the hammer 12 will move downwardly when the feed of 15 the trunk is in the opposite direction. A connecting rod 29 having its upper end portion pivotally connected to the wrist pin 26 is provided with a manually operable lever 30 which is fulcrumed on the rod and is 20 connected at one end to the spring pressed bolt 27 to permit the easy withdrawal of the bolt from the bolt openings in changing from one opening to the other to adjust relative movements of the parts. The lower end 25 portion of the connecting rod is adjustably connected to an arm 31 mounted on the rear end of a rock shaft 32, and the rock shaft is journaled on the side portion of the upstanding column 10. A vertically extending arm 33 mounted on the front end portion of the rock shaft 32 is connected to one 30 end of a connecting rod 34. The opposite end of the connecting rod is pivoted to a 35 slidable block 35 which carries a spring pressed dog 36 having its lower end of angular formation to freely snap over the teeth of the rack bar 37 during the retrieving stroke to the left of the slidable block. During the working stroke to the right the 40 dog will positively engage the teeth and move the said rack bar a predetermined distance. The dog 36 extends upwardly through the block and carries fast thereon a collar 37 which is provided with a downwardly extending pin 37'. This pin is 45 adapted to removably enter either one of two openings 39 formed in the slidable block to permit turning the dog 36 to reverse the direction of the working stroke thereof. The 50 spring of the dog will hold the parts in adjusted position and by lifting and turning the dog a one quarter turn the pin 37' will rest on the upper surface of the slidable block and hold the dog out of engagement 55 with the rack bar. The upper end portion of the spring pressed dog is provided with a knob or handle 36' for convenience in lifting or turning the dog.

The rack bar 37 is adjustably mounted 60 on the slidable bar by a bolt and slotted connection 38 and an adjusting screw 39 to adjust the position of the trunk with relation to the riveting portion of the machine.

In riveting the angled edge parts 40 to 65 the trunk panels or sides 41 before said

panels are joined together, supporting brackets 42 are adjustably bolted to the slid- 70 able bar 17 in spaced relation as shown in Fig. 6 for holding said panels and the angled edge parts in proper position with re- 75 lation to the riveting portion of the ma- 80 chine.

The transversely extending slidable mem- 75 ber 21 is also provided with a rack bar 43 for intermittently moving the supporting arms 23 toward or away from the upstand- 80 ing column 10. The rack bar and the sup- 85 porting arms 23 are moved by a spring pressed dog 43' which is carried by a slid- 90 able block 44 mounted on one side portion 95 of the guide arm 18. The dog is similar to the dog 36 and is provided with a fixed col- 100 lar 45 having a depending pin 46 which is adapted to enter either one of two openings 47 to adjust the direction of movement of the rack bar. The dog is also provided with a knob or handle 48 for adjusting the dog in the same manner before described with relation to the dog 36.

The block 44 is slidably mounted on the 90 side portion of the arm 18 and has a link connection 48 with an upstanding arm 49 slidably mounted on a transversely extending rock shaft 50 of rectangular shape in cross section. Said arm 49 is formed with a 95 rectangular opening 49' to fit the rock shaft 50 so that it will be rocked thereby and is maintained in its position with relation to the arm 18 by bearings 51 which surround the shaft on opposite sides of the arm 49, 100 thus causing said arm 49 to move trans- 105 versely with the arm 18. The rock shaft 50 is journaled and supported from the oppo- 110 site end portions of the transversely extend- 115 ing guide member 16. One end of the rock shaft 50 is provided with an arm 52 fast thereon which has a vertically extending link connection 53 with one end of a bell crank lever 54 fulcrumed on the upper por- 120 tion of the transversely extending guide member 16. A horizontally extending link 55 connects the other end of the bell crank lever 54 to the vertically extending arm 33 before described thus reciprocating the dog 43 from the same rock shaft 32 that recipro- 125 cates the other dog 36.

A foot pedal 56 controls the operation of the machine in the ordinary manner.

In use one of the trunk panels or sides is placed on the supporting arms 42 and the angular edge strip is then the edge of the panel in proper position so that the first rivet perforation of the strip will register with the riveting portion of the machine, if the start is to be made from the front edge of the panel the dog 43 is placed in operable position and the dog 36 is disengaged from its rack. The machine is now started and the panel will receive a rivet through the first perforation of the edge strip and said 130

rivet will be driven through the edge portion of the panel and set on its tubular end portion spread. As soon as this operation is completed the movable hammer arm will be raised and while traveling upwardly the supports with the panel and attached strip will be moved inwardly toward the column 10 the distance of one perforation and the hammer will again descend and drive 15 another rivet as before described. This operation will continue as long as the foot pedal is depressed. When the end of the strip has been reached the lower dog 43 is 20 disengaged from its rack and the upper dog 36 moved into engagement with its rack. This adjustment will cause the panel to be moved intermittently in steps across the front of the column and the rear edge strip to be riveted to the panel. When this edge is 25 completed the dogs are changed as before with the exception that the dog 36 is positioned to feed in the opposite direction and the bolt 27 is changed to the other opening 30 to change the relative movement of feed 28 with respect to the travel of the supports. When thus adjusted the panel will be intermittently moved away from the column 10 while receiving rivets. When the edge pieces have been attached to the panel the other panel pieces may then be easily 35 connected to the edge pieces in the same manner described by placing them on the brackets and supporting the panel to which the edge piece has been attached at right angles thereto. When the trunk is partly assembled the brackets 42 may be removed and the parts 40 be supported on the arms 23 as shown in Fig. 1. In either case the riveting operation will be the same.

40 From the foregoing description it will be seen that the automatic riveting machine is of very simple construction and is well adapted for the purpose described.

What I claim as my invention is:

45 1. An automatic riveting machine, comprising a riveting mechanism, means for supporting and intermittently moving predetermined distances in one direction to said riveting mechanism the material to be riveted, and means for intermittently moving the material to the said riveting mechanism in a direction at an angle to the direction first mentioned.

50 2. An automatic riveting machine, comprising a riveting mechanism having a riveting hammer which moves toward and away from its anvil, means for supporting and intermittently moving the material to be riveted predetermined distances in one 55 direction to said riveting mechanism while the riveting hammer is moving away from the anvil, and means for intermittently moving the material to the said riveting mechanism in a direction at an angle to the direction first mentioned.

3. An automatic riveting machine, comprising a standard provided with a riveting mechanism having a riveting hammer which moves toward and away from its anvil, a transversely extending guide member carried by the standard, a slidable material holder mounted on the guide member, means for intermittently moving the holder predetermined distances in one direction after each riveting operation, an outwardly projecting guide arm carried by the slidable material holder, a slidable material holder mounted on the projecting guide arm, and means for intermittently moving the last mentioned material holder predetermined 70 distances in a direction at an angle to the direction of movement of the other holder after each riveting operation.

4. An automatic riveting machine, comprising a standard provided with riveting 85 mechanism, guide arms mounted on the standard and extending at an angle with relation to each other, material holders slidably mounted on the guide arms and movable in directions at an angle with relation 90 to each other, and means for intermittently moving said holders.

5. An automatic riveting machine, comprising a standard provided with riveting mechanism, a pair of guide arms mounted 95 on the standard, material holders slidably mounted on the guide arms and movable in directions approximately at right angles with relation to each other, and means for intermittently moving each of said material 100 holders.

6. An automatic riveting machine, comprising a standard provided with riveting mechanism, guide members mounted on the standard, material holders slidably mounted 105 on the guide members and movable at approximately right angles to each other, said holders having rack bars mounted thereon, dogs movably mounted on the guide members and engaging the rack bars to intermittently move each of said material holders, and means for moving the dogs.

7. An automatic riveting machine, comprising a standard provided with riveting mechanism, a transversely extending guide 115 member mounted on the standard, a slidable bar mounted on the guide member and provided with an outwardly projecting guide arm, a material holder mounted on the projecting guide arm, a material holder 120 removably mounted on the slidable bar, rack bars mounted on both material holders, dogs engaging the rack bars, rock shafts carried by the standard, arms mounted on and rocked by the rock shafts and having a link 125 connection with the dogs, one of said arms having a sliding connection with one of the rock shafts, and means for transmitting motion from the riveting machine to the rock shafts.

8. An automatic riveting machine, comprising a standard provided with riveting mechanism, a transversely extending guide member mounted on the standard, a rock shaft of rectangular form in cross section carried by and extending longitudinally of the guide member, a slideable bar mounted on the guide member and provided with an outwardly projecting guide arm, a material holder mounted on the slideable bar, a rack bar mounted on the material holder, a dog reciprocally mounted on the transverse member and engaging the rack bar, a rock shaft carried by the standard and having an arm and a link connection with the dog, means for rocking the rock shaft, a material holder slidably carried by the outwardly projecting arm and provided with a rack bar, a dog reciprocally mounted on the projecting arm and engaging the last mentioned rack bar, an arm slidably mounted on and rocked by the rock shaft of rectangular form in cross section and having a linked connection with the dog of the projecting arm, and means for rocking the last mentioned rock shaft.

9. An automatic riveting machine, comprising a standard provided with riveting mechanism, a transversely extending guide member mounted on the standard, a rock shaft of rectangular form in cross section carried by and extending longitudinally of the guide member, a slideable bar mounted on the guide member and provided with an outwardly projecting guide arm, a material holder mounted on the slideable bar, a rack bar mounted on the material holder, a dog reciprocally mounted on the transverse member and engaging the rack bar, a rock shaft carried by the standard and having an arm and a link connection with the dog, means for rocking the rock shaft, a material holder slidably carried by the outwardly projecting arm and provided with a rack bar, a dog reciprocally mounted on the projecting arm and engaging the last mentioned rack bar, an arm slidably mounted on and rocked by the rock shaft of rectangular form in cross section, a link connection between said slideable arm and the dog mounted on the projecting arm, an arm mounted on one end of the rock shaft of rectangular shaft in cross section, a bell crank lever mounted on one end portion of the transverse guide member and having a link connection with the rock shaft arm, a link connection between the bell crank lever and the arm of the rock shaft mounted on the standard, and an arm and a link connection between the standard rock shaft and the driving mechanism of the machine.

10. An automatic riveting machine, comprising a standard provided with riveting mechanisms, a transversely extending guide member mounted on the standard, a rock

shaft of rectangular form in cross section carried by and extending longitudinally of the guide member, a slideable bar mounted on the guide member and provided with an outwardly projecting guide arm, a material holder mounted on the slideable bar, a rack bar mounted on the material holder, a reversible dog reciprocally mounted on the transverse member and engaging the rack bar, a rock shaft carried by the standard and having an arm and a link connection with the dog, means for rocking the rock shaft, a material holder slidably carried by the outwardly projecting arm and provided with a rack bar, a reversible dog reciprocally mounted on the projecting arm and engaging the last mentioned rack bar, an arm slidably mounted on and rocked by the rock shaft of rectangular form in cross section, a link connection between said slideable arm and the dog mounted on the projecting arm, an arm mounted on one end of the rock shaft of rectangular shape in cross section, a bell crank lever mounted on one end portion of the transverse guide member and having a link connection with the rock shaft arm, a link connection between the bell crank lever and the arm of the rock shaft mounted on the standard, and an arm and a link connection between the standard rock shaft and the driving mechanism of the machine.

11. An automatic riveting machine, comprising a standard provided with riveting mechanism, a transversely extending guide member mounted on the standard, a rock shaft of rectangular form in cross section carried by and extending longitudinally of the guide member, a slideable bar mounted on the guide member and provided with an outwardly projecting guide arm, a material holder mounted on the slideable bar, a rack bar mounted on the material holder, a dog reciprocally mounted on the transverse member and engaging the rack bar, a rock shaft carried by the standard and having an arm and a link connection with the dog, means for rocking the rock shaft, a material holder slidably carried by the outwardly projecting arm and provided with a rack bar, a dog reciprocally mounted on the projecting arm and engaging the last mentioned rack bar, an arm slidably mounted on and rocked by the rock shaft of rectangular form in cross section, a link connection between said slideable arm and the dog mounted on the projecting arm, an arm mounted on one end of the rock shaft of rectangular shape in cross section, a bell crank lever mounted on one end portion of the transverse guide member and having a link connection with the rock shaft arm, a link connection between the bell crank lever and the arm of the rock shaft mounted on the standard, and an arm and a link connection between the standard rock shaft and the driving mechanism of the machine.

tween the standard rock shaft and the driving mechanism of the machine, said arm and link connection being connectible with the driving mechanism at a plurality of positions to change the relative movement of the material supports with relation to the riveting operation.

12. An automatic riveting machine, comprising a standard provided with riveting mechanism and a revoluble member having a wrist pin adjustably connectible thereto at each of a plurality of points, a transversely extending guide member mounted on the standard, a rock shaft of rectangular form in cross section carried by and extending longitudinally of the guide member, a slideable bar mounted on the guide member and provided with an outwardly projecting guide arm, a material holder mounted 15 on the slideable bar, a rack bar mounted on the material holder, a dog reciprocally mounted on the transverse member and engaging the rack bar, a rock shaft carried by the standard and having an arm and a 20 link connection with the dog, means for rocking the rock shaft, a material holder slidably carried by the outwardly projecting arm and provided with a rack bar, a dog reciprocally mounted on the projecting arm 25 and engaging the last mentioned rack bar, an arm slidably mounted on and rocked by the rock shaft of rectangular form in cross section, a link connection between said slideable arm and the dog mounted on the projecting arm, an arm mounted on one end of 30 the rock shaft of rectangular shape in cross section, a bell crank lever mounted on one end portion of the transverse guide member and having a link connection with 35 the rock shaft arm, a link connection between the bell crank lever and the arm of the rock shaft mounted on the standard, and an arm and a link connection between 40 the standard rock shaft and the wrist pin of the revoluble member.

13. An automatic riveting machine, comprising a standard provided with riveting mechanism and a revoluble member having radially opposite openings, a wrist pin member revolubly connected to the revoluble 50 member and having a tubular wrist pin, a bolt extending through said wrist and adapted to enter one of the openings of the revoluble member, means for moving said bolt, an arm and a link connection between 55 the standard rock shaft and the tubular wrist pin, a transversely extending guide member mounted on the standard, a rock shaft of rectangular form in cross section carried by and extending longitudinally of 60 the guide member, a slideable bar mounted on the guide member and provided with an outwardly projecting guide arm, a material holder mounted on the slideable bar, a rack bar mounted on the material holder, a dog 65 reciprocally mounted on the transverse member and engaging the rock bar, a rock shaft carried by the standard and having an arm and a link connection with the dog, means for rocking the rock shaft, a material holder 70 slidably carried by the outwardly projecting arm and provided with a rack bar, a dog reciprocally mounted on the projecting arm and engaging the last mentioned rack bar, an arm slidably mounted on and rocked by 75 the rock shaft of rectangular form in cross section, a link connection between said slideable arm and the dog mounted on the projecting arm, an arm mounted on one end of the rock shaft of rectangular shape in cross 80 section, a bell crank lever mounted on one end portion of the transverse guide member and having a link connection between the bell crank lever and the arm of the rock shaft mounted on the standard, and an arm and a link connection between the standard rock 85 shaft and the driving mechanism of the machine.

In testimony whereof I affix my signature.
FREDERICK J. GREENE.
